Inventor:
JOSEPH VAN KIEK BORLAND,

D. Anthony Neira
his Attorney

UNITED STATES PATENT OFFICE.

JOSEPH VAN KIRK BORLAND, OF CLAIRTON, PENNSYLVANIA.

BY-PRODUCT COKE OVEN AND METHOD OF OPERATING SAME.

Application filed September 13, 1923. Serial No. 682,497.

This invention relates to a method of and apparatus for providing a uniform distribution of fuel gas to by-product coke ovens of the by-product type, and has for its object the provision of a novel method of and apparatus for providing a uniform distribution of the fuel gas to coke ovens of the by-product type, whereby uniform heating of each of the ovens will be obtained.

Another object is to provide a method and apparatus, such as described above, which will cause greater gas economy, due to the better temperature regulation resulting from improved control of the gas distribution obtained by maintaining the gas in the fuel gas main at a uniform temperature.

Experience has shown that in operating the by-product coke ovens of the Koppers and similar types, the ovens farthest from the point of source of the fuel gas were heated to a less degree than the ovens closer to the source. Various experiments were made in an attempt to overcome this objection. The pressure was regulated so as to be substantially constant and the same throughout the fuel gas main, and the outlets to each oven were regulated so as to be uniform, and even with an equal volume and pressure of gas entering into each oven they became progressively cooler as they progressed from the source of supply.

The fuel gas main extends parallel with and in close proximity to the ovens of the type to which this invention pertains. The present applicant has discovered that the gases as they pass through this main absorb or take up the heat radiated from said ovens, and become progressively hotter as they travel, so that the gases become rarified and of less density as they progress through the main, and, therefore, have less calorific value per cubic foot as they progress through the main from the source of supply. Applicant has insulated the fuel gas main so as to prevent the gases from taking on the heat radiating from the ovens, and in doing so is enabled to get a uniform density of gas throughout the main. Therefore, when uniform pressure and uniform outlets are provided applicant by insulating the main is enabled to provide a uniform supply of gas of uniform quality to each of the ovens along the length of the main, and thus get a uniform temperature throughout the several ovens.

In the drawings, Figure 1 is a somewhat

diagrammatic front elevation of a battery of coke ovens, showing the location of the fuel gas main having my invention applied thereto.

Figure 2 is a partial sectional elevation on the line II—II of Figure 1.

Referring more particularly to the drawings, the numeral 2 designates the battery of ovens as a whole, which is composed of a plurality of ovens 3 separated, one from another, by a series of vertical flues 4, in which the fuel gas is burned to provide the heat necessary for coking. An air regenerator 5 is provided below each coking chamber and is adapted to preheat the air for combustion in the flues.

A fuel gas main 6 extends along the entire battery of ovens 2 in close proximity thereto, and adapted to be supplied with gas under pressure from a suitable gas holder of standard design (not shown). The main 6 is connected by suitable risers 7, and a gas gun 8 to a gas duct 9 extending under the flues 4. The duct 9 opens into the flues 4 through suitable nozzles 10 and gas ports 11.

The ovens as described above are of the standard Koppers type, well known in the art, and will, therefore, not be described or illustrated more in detail.

Heretofore it has been found impossible to obtain uniform heating of the several successive ovens of the battery, and after many experiments and tests, as set forth in the fore part of this specification, the applicant has found that this was due to the gases taking on heat while passing through the main.

The main 6 is from 20 feet to 375 feet in length, according to the size of the ovens, and is located close to the ends of the regenerators of the battery, and consequently is subjected along its entire length to the great amount of heat radiating from the walls of the regenerators.

The applicant has, therefore, provided an insulating covering 12 around the pipe or main 6 of sufficient thickness to prevent the heat from the oven regenerators reaching the gas in the main. By thus insulating the main 6 the applicant provides for delivery of the gases to all the ovens at the same, or substantially the same, temperature. In order to get a uniform heating of all the ovens he provides the usual gas supply from the gas holder, of uniform or fixed pressure

to the main, and provides uniform outlets from the main to the flues 4, and these, together with the insulated main, provide for the delivery of a uniform quantity of gas, of uniform temperature and density, and substantially the same calorific value per cubic foot to each successive flue of the several ovens, whereby uniform heating of all the ovens is obtained.

19. While only the one specific embodiment of my invention is described in the foregoing specification and illustrated in the accompanying drawings, it will be understood that I do not wish to be limited to such construction, since various modifications may be made without departing from the scope of my invention as defined in the appended claims.

I claim:

20. 1. In the operation of a battery of by-product coke ovens, having a fuel gas main for supplying fuel gas to each of the ovens of said battery, the method of providing uni-

form distribution of the fuel gas from said main to each oven of said battery of ovens, which includes as a step, maintaining the gases at substantially a uniform temperature throughout the entire length of the fuel main.

2. The combination with a battery of by-product coke ovens having a fuel gas main parallel therewith, and outlets from said main leading to each of said ovens, of means for maintaining a uniform temperature within said main over the entire length thereof.

3. The combination with a battery of by-product coke ovens having a fuel gas main parallel therewith, and outlets from said main leading to each of said ovens, of an insulating covering on said main adapted to prevent the gases taking on heat from said ovens.

In testimony whereof I have hereunto signed my name.

JOSEPH VAN KIRK BORLAND.
